UNITED STATES PATENT OFFICE.

HERBERT G. BEEDE, OF PAWTUCKET, RHODE ISLAND.

RING TWISTING OR SPINNING DEVICE.

Application filed February 3, 1922. Serial No. 533,798.

To all whom it may concern:

Be it known that I, HERBERT G. BEEDE, a citizen of the United States of America, and resident of Pawtucket, in the county of Providence and State of Rhode Island, have invented new and useful Improvements in Ring Twisting or Spinning Devices, of which the following is a specification.

This invention concerns ring twisting or spinning mechanism and relates more particularly to a ring and traveler of that type commonly employed in the twisting and spinning of relatively heavy yarns or cords. Although the invention is primarily intended for twisting, it may also be used for spinning certain materials, such as jute or linen, and its broader application to both twisting and spinning is contemplated by the claims.

20 In the operation of the older type of twisting mechanism which is well adapted for the twisting of fine yarns, the vertical traveler employed is subjected during its movement both to the drag of the yarn and to centrifugal action. With such an arrangement a properly weighted traveler tends to balance about the lower flange of the ring under the opposing action of centrifugal force and the yarn pull and under 25 such circumstances any undue increase in speed results in increased centrifugal force with a corresponding increase in frictional drag of the traveler upon the ring, while additional tension on the yarn tends to decrease such drag, the speed of revolution of the traveler being thus automatically controlled. In starting the machine the yarn pull is relatively large, thus decreasing the frictional drag and permitting the traveler 30 quickly to come to normal speed, while in stopping, the pull of the yarn is reduced substantially to zero and centrifugal action serves quickly to bring the traveler to rest without overrunning.

45 In the devices disclosed in patents to Herbert G. Beede Nos. 1,075,004, October 7, 1913 and 1,174,961, March 14, 1916, an arrangement suitable for the twisting and spinning of heavy yarns or cords is disclosed in which 50 the speed of the revolving ring or traveler is automatically controlled by centrifugal action alone. The arrangements disclosed in these patents serve to exert a varying centrifugal drag upon the revolving ring directly in accordance with variations in the speed of the latter, thus effectively control-

ling such speed during normal running of the machine, but as the latter slows down in stopping, the centrifugal drag on the revolving ring is decreased simultaneously with the cessation of yarn pull, thus permitting the revolving ring to run ahead and tangle the yarns.

The object of the present invention is accordingly to provide an arrangement useful in connection with twisting or spinning devices of the general type disclosed in the aforesaid patents, such that the velocity of the revolving ring may be made dependent both upon centrifugal action and the pull imposed by the yarn, whereby in starting, the yarn will not be subjected to undue strain, and in stopping, the revolving ring will come to rest promptly and without running ahead.

75 The above object may well be accomplished by the employment of a device such as is illustrated by way of example in the accompanying drawings, in which,—

Fig. 1 is a plan view of the device of the present invention, certain parts being broken away to illustrate the interior construction, the position of the winding spindle and yarn being indicated in dotted lines;

Fig. 2 is a diametral, vertical cross section through the device of Fig. 1 on a line such as 2—2 thereof, but showing the two brake devices as occupying relatively different positions; and

Fig. 3 is a fragmentary side elevation showing one of the yarn guides and associated parts.

In the drawings the numeral 1 indicates a portion of the rail of a spinning frame or twister, such rail being provided with an opening for the reception of the stationary ring 2. This ring comprises an upstanding flange 3, a substantially parallel upstanding flange 4, and a downwardly directed flange 5, the two last named flanges being substantially in alignment and providing the cylindrical inner surface 6. Within the channel between the flanges 3 and 4 is arranged the revolving traveler ring comprising the cylindrical ring member 7 and the annular plate 8, the members 7 and 8 being suitably secured together as by means of screws 9. The member 7 is provided upon its exterior surface with a ball race groove 10 which cooperates with a complementary groove in a ring 11, also seated within the channel between the flanges 3, 4, and secured to the

flange 3 by means of screws such as 12. Within the ball race thus provided are arranged ball bearings 13 and, if desired, the individual bearings may be held in spaced 5 relation by means of a suitable cage 14 having slots or openings for the reception of the several balls. The traveler ring as thus arranged may be rotated very easily within the stationary ring, while the bearings for such ring are well protected from 10 dirt or fly.

Suitable yarn guides are provided in accordance with the number of yarn ends to be twisted together. In the present instance, 15 two such guides are illustrated, these guides comprising the plates 15, 16 respectively, which rest upon the upper surface of the annular member 8, such plates being provided at opposite ends with radially elongate slots 17. Screws 18 pass loosely through such slots and engage threaded openings in the member 8 whereby the plates 15, 16 are permitted to move slightly in a radial direction but are secured to the revolving ring for rotation therewith. Depending from the inner edges of the respective plates 15, 16 are the members 19, 20, constituting brake shoes for engagement with the inner cylindrical surface 6 of the 30 stationary ring 2. Mounted upon the plates 15, 16 are yarn guide eyes 21, 22 respectively, such eyes being integral with the plates 15, 16, or, if desired, formed as separate elements suitably secured thereto. As 35 indicated in Fig. 1 the yarn Y passes through the guide eye 21 for twisting with a similar yarn (not shown) passing through the eye 22, as such yarns are wound upon the spindle.

40 In the operation of the above device, it being assumed that the spindle is stationary, a considerable tension or drag is placed upon the yarn Y as the spindle starts to rotate, so that if the guide eyes are not already in 45 positions corresponding to that illustrated at the left of Fig. 2, they will immediately be pulled inwardly to occupy such a position. As thus positioned, the brake members 19, 20 are out of contact with the surface 6 of the 50 stationary ring and thus the drag of the yarn may readily impart a rotating movement to the revolving ring about the axis of the spindle without having to overcome any frictional resistance other than that of 55 the ball bearings. As the ring speeds up, centrifugal force tends to move the plates 15 and 16 with their brake shoes 19, 20 outwardly until such shoes occupy positions such as indicated at the right-hand side of 60 Fig. 2. As thus arranged, the brake shoes, by contact with the surface 6, offer a certain amount of frictional resistance to the rotation of the revolving ring. This centrifugal action during normal operation varies 65 in accordance with the speed of rotation of

the revolving traveler ring, while the drag of the yarn acts in opposition to centrifugal force, the two forces tending to balance one another, so that the brake device thus provided tends automatically to retard the speed of rotation of the revolving ring. When the winding spindle S is stopped, the momentum of the relatively heavy revolving traveler ring with its brake devices tends to continue its rotating movement, and if such movement should continue for any appreciable time there would be a tendency to tangle the several yarn ends which at this time are free from any substantial tension. The removal of tension upon the yarn ends 80 however, permits centrifugal force to act without restraint upon the plates 15 which thus move freely outwardly, bringing the brake shoes 19, 20 firmly against the inner surface 6 of the stationary ring thereby imposing an effective braking action which serves to bring the revolving ring to rest very quickly. It will thus be evident that in starting, the drag upon the yarn is sufficient to overcome the action of the brake devices thus permitting the revolving ring to speed up rapidly, while in stopping, the cessation of drag upon the yarn permits the full effect of centrifugal action to be applied to the brake devices thus stopping the traveler quickly.

While a specific arrangement for mounting the revolving traveler ring in the stationary ring has been illustrated herein, it is to be understood that in so far as the 100 automatic control of the action of the revolving ring is concerned, such precise arrangement is immaterial except in so far as it tends to reduce friction between the stationary and rotating parts, thus making the brake device more sensitive in operation than would be the case were the revolving ring less free to move.

What I claim and desire to secure by Letters Patent of the United States is:

1. A ring spinning or twisting device comprising a ring rotatable about its own axis, and automatic means comprising a yarn engaging element for regulating the speed of rotation of said ring both in normal operation and in stopping.

2. A ring spinning or twisting device comprising a stationary ring, a revolving ring coaxial therewith, and means carried by said revolving ring and operable conjointly by the pull of the yarn and by centrifugal force for regulating the speed of movement of said revolving ring.

3. A ring spinning or twisting device comprising a ring arranged for rotation about its own axis, and brake means movable relatively thereto for controlling the speed of rotation of said ring, the action of said brake means being regulated by the pull of the yarn.

4. A ring spinning or twisting device comprising a revolving ring arranged for rotation about its own axis, a brake device mounted upon said ring and operative under centrifugal action to retard said ring in its rotation, and means whereby the pull of the yarn is transmitted to the brake device in opposition to such centrifugal action. 35
5. A ring spinning or twisting device comprising a ring arranged to rotate about the axis of the winding spindle, and a combined brake device and yarn guide mounted upon said rotating ring and freely movable radially thereof to a limited extent under 40 the action of centrifugal force.
6. A ring spinning or twisting device comprising a revolving ring, a weighted brake member carried by said ring and movable relatively thereto, and a yarn guide eye 45 secured to said brake member.
7. A ring spinning or twisting device comprising a stationary ring having a brake surface, a ring rotatably supported by the stationary ring, a member mounted upon the revolving ring and freely movable radially with respect thereto under the action of centrifugal force, a weighted brake shoe carried by said member and engageable with the brake surface of the stationary ring, and 50 a yarn guide mounted upon said member.
8. A ring spinning or twisting device comprising a stationary ring, a ring mounted for rotation relatively thereto, antifriction bearings interposed between said rings, a 55
- brake supporting plate upon said rotating ring, said plate having a radially elongated slot, securing means passing loosely through said slot for connecting said plate to the revolving ring, and a yarn guide device mounted upon the plate. 60
9. A ring spinning or twisting device comprising a stationary ring having an annular channel therein, a revolving ring having a flange seated within said channel, antifriction bearings interposed between said 65 flange and an element fixed to the stationary ring, a radially movable plate mounted upon the revolving ring and freely movable relatively to the latter under the action of centrifugal force, and a brake shoe member depending from the inner edge of said plate and engageable with the inner surface of the stationary ring. 70
10. A device of the class described comprising a stationary ring having an annular channel in its upper surface, a composite revolving ring consisting of a cylindrical ring fitting within said channel and having a ball groove in its outer face and a cover ring secured to the cylindrical ring and providing a substantially horizontal upper surface, ball bearings interposed between said ball groove and a similar groove in a part fixed relatively to the stationary ring, and a 75
- yarn guide fixed to the cover ring. 80

Signed by me at Pawtucket, Rhode Island,
